UNITED STATES PATENT OFFICE.

JOHN REBAR, OF SMITHDALE, PENNSYLVANIA.

ELECTRIC SIGNAL.

No. 885,519.

Specification of Letters Patent.

Patented April 21, 1908.

Application filed November 11, 1907. Serial No. 401,585.

To all whom it may concern:

Be it known that I, JOHN REBAR, a citizen of the United States of America, residing at Smithdale, in the county of Allegheny and 5 State of Pennsylvania, have invented certain new and useful Improvements in Electric Signals, of which the following is a specification, reference being had therein to the accompanying drawing.

10 This invention relates to electric signals for railway trains, and its primary object is, to provide a simple and inexpensive signaling device whereby the engineer may be communicated with from convenient points 15 throughout the length of the train.

A further object of the invention is to provide signaling apparatus comprising resiliently supported contacts preferably carried by the car couplers, and adapted to have a 20 wiping frictional contact.

The construction of the improvement will be fully described hereinafter in connection with the accompanying drawing which forms a part of this specification, and its novel features will be set forth in the appended claims.

In the drawing: Figure 1 is a diagrammatic view of a railway train equipped with my improved signaling apparatus, Fig. 2 is a top plan view of two interlocked coupler heads, with my improved disk contacts secured thereto by resilient arms, Fig. 3 is a front elevation of the coupler-heads with contact disks secured at the sides of the same, and Fig. 4 is a vertical transverse section 35 through one of the contact disks and its supporting spring.

The reference numeral 1 designates a signal bell located in the locomotive cab, a battery 2 being also located in the cab or at some convenient point.

The conductor 3 from one side of the battery is electrically connected to a disk 4 mounted upon a bolt 5 extending through an opening in the outer end of a curved spring 6, 45 the inner end of which is secured to the coupler head 7. The spring 6 is insulated from the bolt 5 and disk 4, and as the conductor wire 3 is attached to the bolt the circuit is through the bolt and disk. The disk 4 bears 50 against a similar disk 8 supported by the adjacent coupler head 9 by a curved spring 10 and this disk is connected by a wire 11 with a similar disk 12 at the opposite end of the car and so on throughout the length of the train. 55 The conductor 13 from the opposite side of

the battery is connected to a disk 14 supported at the opposite side of the coupler head 7 by a spring 15, and contacts with a disk 16 secured to the coupler head 9 by a curved spring 17. The disk 16 is electrically connected to a similar disk at the opposite end of the car, each car of the train being provided with two pair of contact disks at each end arranged at the sides of the coupler heads as shown, said disks and their connecting wires 60 and the wires 3 and 13 constituting the battery circuit which is normally open. To close this circuit and ring the bell I employ a plurality of circuit closers 18 located preferably one at each end of the car and by means 65 of these circuit closers which may be push buttons, or switches of any approved form, the battery circuit may be closed at the various points indicated in the diagram.

It will be noted that the several disks employed are pressed out centrally providing a concavo-convex hub 19, and a flat circular bearing surface 20 to insure a good contact between the oppositely disposed disks. The spring arms afford a resilient support for the 80 contact disks and permit the meeting faces thereof to rub against each other with a wiping contact, which not only insures a good electrical contact, but also prevents corrosion of the disks.

If preferred the one pair of disks as 14 and 16, may be omitted, and the return current to the battery may be through the couplers and other metallic elements below the car body.

I would have it understood that the invention also includes all such other modifications and variations in the details of construction as may fall within the terms and scope of the claims.

Having now described my invention what I claim as new, is:—

1. A railway train signal system, comprising a signal bell, a battery, a circuit from the battery to each car of the train, contacts carried on opposite sides of the couplers of said cars, each contact comprising a contact-disk, a curved spring arm having its inner end attached to the coupler and the said disk attached to its outer end and insulated therefrom, the said disks being included in said circuit, and circuit closers on each car, substantially as described.

2. In a railway train signaling system, the combination with a signal bell, a battery, and

a circuit from the battery of each car of the train, of contacts carried on opposite sides of the couplers of said cars, each contact comprising a disk having a projecting hub, a curved spring arm attached at its inner end to one side of a coupler head and having said disk attached to its outer end and insulated therefrom, the said disks having the circuit

wires connected direct thereto, and circuit closers in each car for said circuit. 10

In testimony whereof I affix my signature in the presence of two witnesses.

JOHN REBAR.
